Primary Examiner — Keith J Wilson

(74) Attorney, Agent, or Firm — MCDONNELL
BOEHNEN HULBERT & BERGHOFF LLP(57) **CLAIM**

The ornamental design for an aerosol can activator, as shown and described.

DESCRIPTION

FIG. 1 is a perspective view of the activator viewed from the front and right of and below my new design for an aerosol can activator;

FIG. 2 is a perspective view of the activator viewed from the front and left of and above my new design for an aerosol can activator;

FIG. 3 is a right side elevation view thereof;

FIG. 4 is a left side elevation view thereof;

FIG. 5 is a top plan view thereof;

FIG. 6 is a bottom plan view thereof;

FIG. 7 is a back side view thereof; and,

FIG. 8 is a front side view thereof.

The broken line showing is for the purpose of illustrating portions of the article and forms no part of the claimed design. The broken line which defines the bounds of the claimed invention forms no part of the claimed design.

1 Claim, 6 Drawing Sheets
